UNITED STATES PATENT OFFICE.

ROBERT J. SHEEHY, OF NEW YORK, N. Y.

RAILWAY-SIGNAL.

No. 829,606.

Specification of Letters Patent.

Patented Aug. 28, 1906.

Application filed May 5, 1903. Renewed January 22, 1906. Serial No. 297,222.

To all whom it may concern:

Be it known that I, ROBERT J. SHEEHY, a citizen of the United States, residing at the city of New York, in the borough of Manhattan and State of New York, have invented 5 certain new and useful Improvements in Railway-Signals, of which the following is a full, clear, and exact description.

This invention relates to automatic electric railway-signals adapted either for single or double track roads and designed to afford the greatest degree of safety and sureness of operation with a minimum amount of wiring and apparatus.

15 In accordance with my invention the signals are placed upon the trains, usually in the cab of the locomotive or the compartment occupied by the motorman. The track is divided into blocks, as usual, and my system 20 is so arranged that the proximity of trains either approaching or following each other is indicated for either direction of travel without the use of any electrical conductors between blocks, except the rails upon which 25 the trains run.

My invention will be described in detail with reference to the accompanying drawings, in which—

Figure 1 is a conventional plan of a railway-track and the apparatus and circuits located at each end of a block thereof, and Fig. 2 is a similar view of the apparatus and circuits carried by the locomotive.

I will first describe the apparatus carried 35 by the locomotives. There is a battery A, an electromagnet B, having an oscillating armature-lever *b*, a normally-lighted pilot-lamp *a*, visual and audible signals *c* and *d*, respectively, to act as danger-signals, and an indicator C, whose electromagnet *e* is normally 40 in series with magnet B and whose armature carries an index *e'*, the coils of magnet *e* also serving as a balancing resistance, as will be hereinafter explained. On the truck of the 45 car or train is mounted a contact-lever *f*, pivoted at *f'* and carrying at one end a contact-roller *f''* and at the opposite end adapted to engage a terminal *f'''*, against which the lever is ordinarily held by a spring, as shown. 50 From the battery one side of the circuit leads by wire 1 to the truck-frame and car-wheels. From the other side the circuit leads by wire 2 through magnet B, wire 3, to lever *f*, terminal *f'''*, wire 4, indicator-magnet *e*, wire 5, and

wire 6 to battery. Thus both magnets are 55 normally energized and while in this condition the pilot-lamp *a* is supplied with current over a branch-circuit leading from wire 2 to the armature-lever *b*, contact 7, wire 8, lamp *a*, and wire 6 to the opposite terminal of the 60 battery.

The two rails of a single-track road are indicated by *g* and *g'*. They are divided into blocks or sections by insulation *g''*. If trains run in both directions over this track, auxiliary contact-rails *h* are arranged adjacent to each of the main rails, those on one side being for trains going in one direction, while those on the other side are for trains going in the opposite direction. These contact-rails begin at points adjacent to the insulation *g''* and extend backward a sufficient distance to enable the train to stop after it makes contact with it and before it passes it. The lever *f*, carried by the locomotive, may be assumed to 70 be located on the right-hand side of the train in such a position that the roller *f''* will ride upon the rails *h* upon the same side of the track, said lever *f* being tilted thereby and withdrawn from the terminal *f'''*. At the adjacent ends of the blocks are located two sets of apparatus, one coöperating with the trains going in one direction and the other with the trains going in the opposite direction; but the apparatus for one direction coöperates in a 75 measure with the apparatus for the other direction at a distant end of the block.

The apparatus for trains moving in one direction—say from west to east—consists of a battery I and two electromagnets J and K, 80 respectively. Magnet J has two windings, the second one being indicated by *j''* and consisting of a few turns only. Magnet J actuates two armature-levers *j* and *j'*, both having front and back stops and the former having a lighter spring than the latter, so that the magnet must be stronger to pull up lever *j'* than to pull up the lever *j*. Magnet K has a single armature-lever *k* with front and back 85 stops.

The apparatus for trains traveling from east to west consists of a battery O and two electromagnets L and M, each having a single armature-lever *l* and *m* with their front and back stops.

100 The various circuits will be traced in connection with the description of the operation, which now follows. The condition in which

the apparatus is shown is that when no trains are on the blocks. Magnet J at one end of block X and magnet L at the other end of the same block are energized by battery I, over 5 the following circuits: first, from battery by wires 9 and 10, magnet J, wire 11, main rail g', wire 12, lever k, wire 13, and battery; second, from battery by wires 9 and 10, main rail g', wire 14, magnet L, wire 15, main rail 10 g', wire 12, lever k, wire 13 to battery. The current flowing through J is sufficient to hold up lever j, but not lever j', and the current in magnet L holds up lever l. All other levers are on their back stops as the magnets are 15 deenergized.

Let us now assume a train to approach from the west and to have a clear track ahead. Its roller f² runs onto rail h at the end of block Y and disconnects the terminal f³. The 20 circuit of indicator C being thus opened, the index e' moves to the opposite position, thus showing to the engineer when he strikes the auxiliary rail. This indicator may be a bell, if desired, but it serves to call the engineer's 25 attention to the signals which are about to follow and informs him when the roller f² is on the auxiliary rail. A circuit can now be traced from battery A on the locomotives as follows: by wire 2, magnet B, wire 3, lever f, 30 rail h, wire 16, lever j', wire 17, magnet K, wire 18, wire 11, coil j², front stop of lever j, through lever j, wire 19, to main rail g', car-wheels and axles and wire 1 to battery. Hence 35 magnet B on the locomotive is now in circuit, with magnet K and coil j² on the roadway instead of with indicator-magnet C. Now the combined resistance of magnet K and coil j² is substantially equal to that of the indicator C. Hence the condition of magnet B remains 40 unchanged and the pilot-lamp continues to burn, thus giving a clear signal. The function of coil j² may best be explained here. It will be seen that the circuit just traced includes the lever j and its front stop. This lever 45 is held by magnet J in circuit with lever k and its back stop, as before traced. This circuit is broken by the energizing of magnet K. Hence coil j², which is energized simultaneously with K, is used to retain lever j against 50 its front stop.

Now suppose a train had preceded the first-mentioned train and had not yet left the block X ahead. The wheels and axles of the train in block X in spanning the two rails g and g' would short-circuit battery I, and thus deprive magnets J and L of current, the short circuit being as follows: from battery I by wires 9 and 10 to rail g, through the wheels and axles to rail g', wire 12, lever K and wire 55 13 to battery. Hence lever j would be against its back stop, so that when the train from the west strikes rail h the circuit before traced will be open at the front stop of lever j. Hence magnet B in the cab will be deen-

ergized and its armature will move to the position shown in dotted lines, the pilot-lamp 65 will go out, and a circuit will be established through the visual signal c and audible signal d, as follows: from battery A by wire 2, armature-lever b, contact 20, wire 21, lamp c, and gong d to battery, thus giving a danger-signal to the train in block Y before it enters block X.

If the train in block X happened to have been traveling west, thus making imminent a 75 head-on collision with the train approaching from the west, it will be seen that the train in X would get a danger-signal the moment it struck the rail h at the end of block X for the reason that the train on the block Y short-circuits the battery I at the west end of the block Y and deenergizes magnet L at the east end of block Y, so that when the train in X strikes the rail h the circuit of magnet B in the cab is opened, as will now be traced: 80 from rail h by wire 22, lever l, at which point the circuit is open, since the lever is on its back stop. Hence the train on block X will be notified in time to come to a stop before colliding with the train on block Y, since 85 the length of the rail h is sufficient within 90 which to stop the train.

We now suppose a train in block Z to be going west with a clear track ahead. When it strikes rail h, terminating at the end of 95 block Z, the closed circuit through the cab-magnet B is maintained and the engineer gets the clear signal, the circuit being as follows through the track apparatus: from rail h by wire 22, lever l, front stop, wire 26, magnet 100 M, wire 27, to main rail. If a train had been short-circuited, magnet L deenergized, and its lever l against its back stop. Hence the circuit before traced for the train on Z would be 105 open at lever l and a danger-signal would be given.

In case the train on the block Z going west strikes the contact-rail h just before another train going east on block Y is on the rail h 110 the latter train will be stopped, because the train on Z will close the circuit of magnet M, which will draw its armature-lever m against its front stop and place battery O across the rails g and g' of block X through the wires 23 115 and 24, and this extra battery, acting in conjunction with battery I, will cause magnet J to pull up its second armature-lever j', so that when the train on Y strikes the rail h its magnet B will be on open circuit, as can 120 easily be traced, and the danger-signal will be given. The train on Y will stop while the train on Z will proceed until it strikes the next rail h at the end of block X, when it will be stopped in the manner before described. 125 As soon as the train leaving Z enters X the battery I will be short-circuited through the wheels and axles and the armature-lever j

will go to its back stop, still leaving the circuit of train on block Y open (at j) and its signal to "danger."

It will thus be seen that when the train on 5 Y got the danger-signal from the train on Z the trains were more than a whole block apart. This fact becomes advantageous in equipping portions of the road where grades occur. If, for instance, the train on Y was a 10 heavy one and running downgrade on slippery tracks, the length of block X would give the train time to stop, notwithstanding the difficulty of stopping under such conditions, and back up before collision with the train 15 approaching from Z. The same operation would take place with respect to the train on Z if that on Y was first to strike its rail h, for it will be seen that the train on Y would energize magnet K and open the circuit of battery 20 I, thus causing magnet L to release its armature and presenting to the train on Z an open circuit and danger signal. Train on Z stops until train on Y reaches the rail h on X, when it too is stopped; but train on Z means 25 while had nearly the whole length of X to stop in and back up.

The contacts o and o' on the M magnets may be used as the terminals of an independent circuit, extending to a signal on a crossing road to give notice that a train is or is not about to pass on the main road.

It will be seen that while a train is running a block battery I is short-circuited and the magnet L behind, as well as the magnet J in front, is deenergized, thus providing for a danger - signal to trains approaching the same block from either direction, and this without the use of wires along the block. If a train ahead is stopped, the train on the 40 block will be held up when it reaches rail h at the end of a block.

Having described my invention, I claim—

1. In a railway signal system, the combination of a track-block, an electromagnet at 45 each end thereof, a battery with which said magnets are connected in parallel through circuits including the two track-rails of the block, local signal-loops at each end of the block controlled by the respective magnets and means for connecting the terminals of 50 the loops with a signal-circuit on a train.

2. In a railway signal system, the combination of a track-block, an electromagnet at each end thereof, a battery energizing both 55 magnets through a circuit including the two rails of the block, local signal-loop circuits at each end of the block controlled by the respective magnets, and train-circuits including signals and adapted to coöperate with 60 said local circuits to produce a signal on the train, substantially as described.

3. In an automatic signaling system, the combination of a single-track road divided into blocks, signal-controlling apparatus at

adjacent block limits, the same being electrically connected together through the intervening rails of the track only, signals on trains and means whereby said signals will be displayed on trains approaching a block from either direction notifying them of the presence of a train in said block regardless of the direction of movement of the latter train.

4. In an automatic signaling system, the combination of a road divided into blocks, a local loop-circuit at the block limit normally terminating at two points on the road side, a signal-circuit on a train including a battery and signal magnet and terminating at two points adapted to engage the first-mentioned two points respectively to throw both circuits into one, an electromagnet and a battery adapted to hold the local circuit normally closed, and a short-circuit to said battery adapted to be closed by spanning the rails.

5. In an automatic signaling system, the combination of a track divided into blocks, a local partial circuit at each block limit including two electromagnets whose armatures control said local partial circuit, a train-circuit including a battery, a signal-magnet and a resistance equal to that of both electromagnets in the local partial circuit, a circuit-closer carried by the train and adapted to connect the local and train circuits together and at the same time cut out the resistance, for the purpose set forth.

6. In an automatic signaling system, the combination of a track divided into blocks, a local partial circuit at each block limit including an electromagnet, a local battery at the block limit, an electromagnet at a distant block limit, a circuit including the battery and distant magnet, a circuit-breaker in said circuit and controlled by said magnet in the local partial circuit and means whereby a train will energize the magnet in the local circuit, substantially as described.

7. In a block-signaling system, the combination with a block, of an electromagnet at one end thereof, a battery normally energizing said magnet, a local circuit including two cut-outs both of which are controlled by said magnet, one being operated on a light current and the other on a heavy current, a second electromagnet at the opposite end of the block, a second battery, a circuit controlled by the second magnet and including the first electromagnet and the second battery, means whereby one train will actuate the second electromagnet and means carried by another train and coöperating with said local circuit to produce a signal for the second train, substantially as described.

8. In a railway signaling system, the combination of a road - side circuit, a road-side battery adapted to be shunted by spanning the rails, an electromagnet normally main-

taining said circuit in condition to give a clear signal, a signal train-circuit, a train-battery and means whereby the train will connect both circuits in one series circuit and 5 actuate the train - signal by means of the train - battery in accordance with the condition of the road-side circuit.

In witness whereof I subscribe my signature in presence of two witnesses.

ROBERT J. SHEEHY.
